UNITED STATES PATENT OFFICE.

LINCOLN L. PORTER, OF OSKALOOSA, IOWA.

CARPET-CLEANING MACHINE.

1,119,114.

Specification of Letters Patent.

Patented Dec. 1, 1914.

Application filed August 19, 1913. Serial No. 785,525.

To all whom it may concern:

Be it known that I, LINCOLN L. PORTER, a citizen of the United States, residing at Oskaloosa, in the county of Mahaska and State of Iowa, have invented certain new and useful Improvements in Carpet-Cleaning Machines, of which the following is a specification.

My invention relates to improvements in carpet cleaning machines, of that type employing an air blast for the purpose of separating the accumulated dust and dirt from the carpet, rug, etc.

The primary object of the invention is to provide an improved machine for disinfecting and cleaning carpets and other fabrics by compressed air, and by means of which the foreign substances are effectively driven from the fabric by the blast of compressed air, and the blast of air is maintained at a high velocity in order to accomplish the work in using the compressed air according to my invention. The air as it escapes from a plurality of nozzles is allowed to reach a very high velocity and then the air after escaping from the nozzles is confined in such a way that it will have no exit except through the material being cleaned.

The invention consists essentially in the combination and arrangement of parts whereby the carpet or material to be cleaned is suspended in an inclosure, and the action of the compressed air on the carpet causes it to vibrate and be "whipped," and in this manner the passing currents of air carry off the dust and foreign matter from the carpet.

In the accompanying drawings I have illustrated one complete example of the physical embodiment of my invention constructed according to the best mode I have so far devised for the practical application of the principles of the invention. I have illustrated some of the minor details and devices of simple form, and have shown the machine as manually operated in certain particulars, but it will be understood that I may use motive power when desirable.

Figure 1 is a broken side elevation of a machine embodying my invention with a part shown in section. Fig. 2 is a part sectional view of the machine of Fig. 1. Fig. 3 is a detail view of the carpet stretching and holding devices. Fig. 4 is a detail view

of means for actuating the carpet holding and stretching devices. Fig. 5 is a side elevation of a part of the machine showing the air nozzles.

In the drawings I have illustrated an exemplification of the invention to show the principles thereof, and in this connection I employ a casing 1 which provides a chamber 2 and at the upper open end of the casing I locate the side boards 3 3', which are provided with rounded upper edges and of smooth surface for the passage thereover of a carpet 4.

The carpet 4 is held upon a pair of drums as 5 and 6, the former being the unwinding drum and the latter the winding drum for the carpet while it is being cleaned. The carpet 4 is passed over the upper open end of the chamber 2 and is wound upon the winding drum 6 by means of a lever 7 which has a pawl 8 to engage the rack wheel 9 on the drum shaft 10. The drum shaft 10 is supported upon brackets 11, and the unwinding drum 5 is supported by means of its shaft 12 in the end brackets 13. It will be noted that the casing 1 is located between the unwinding and winding drums and the carpet is passed from one drum to the other. This means of passing the carpet through the machine is illustrated as a simple device for the purpose, but it will be understood that I contemplate using other means and devices for this purpose as required.

The entire upper end of the casing is closed by a presser board 14. This board extends approximately the full length of the machine, and covers the chamber 2 from end to end. The under surface 15 of the board is rounded and convexed and the board extends down partly over the convexed upper edges of the side boards 3 3'. The presser board is supported from above by means of swivel air cylinders 16 and piston rods 17 each of which is attached at its lower end to the board by means of strap 18. I have illustrated two of these supports for the board, but it will, of course, be understood that as many may be used as are required. The cylinder 16 is closed at its upper end and is swiveled in a plate 19 attached to the beam 20, and the stem 17 is formed with a piston or head 21 inside of the cylinder 16. Thus, by means of com-

pressed air entering through the inlet pipe 22', the presser board and its accessories may be bodily lifted from the casing, and the swiveled joint 22 allows for lateral movement of the board.

Upon the upper surface of the presser board 14 is secured a compressed air pipe or tubing 23, and this is held to the presser board by means of the straps 18. The compressed air pipe is furnished with compressed air through the inlet 24, and at one side of the pipe are arranged a series of nozzles 25, each provided with a valve 26. As clearly seen in Fig. 2 each of these nozzles is pointed 15 in a direction so as to deliver compressed air under one edge of the presser board and between said edge and the carpet which is held between the presser board and the side rail 3' of the casing. In this manner 20 the compressed air at very high velocity is forced in between the carpet and the presser board. While the carpet is being acted on by the compressed air it is necessary that it be stretched taut and held so stretched 25 under the presser board. For this purpose I provide a carpet stretcher located within the casing 1, which is exemplified clearly in Fig. 3, and comprises a rack bar 27 which rests upon the two pivoted arms 28 and 30, said arms being pivoted at 30, 30 at the interior of the lower end of the casing 1. At each end of the rack bar is located a sliding block 31 in which is pivoted an arm 32 having at its upper free end a tooth block 33 which is adapted to engage the carpet. 35 At its lower end the arm 32 is pivoted at 34 in the slide block 31, and a spring 35 between the arm 32 and block 31 urges the arm to swing upward on its pivot 34. There 40 are two of these arms 32 with their accessories, one at each end of the bar, and each of these arms is provided with a pivot pawl 36 which engages the teeth of the rack bar 27. It will be understood that the sliding 45 blocks 31 may be moved bodily on the rack bar 27 after the pawl 36 has been released, and it will also be understood that the arms 32 with their blocks 33 may be moved to position to engage the carpet. After the 50 blocks 33 are in engagement with the carpet, the carpet may be stretched by raising the levers 28, 29 up toward a vertical position. This movement of the levers lifts the rack bar 27 and the sliding blocks 31 with it, and the lifting action of the rack bar 27 causes 55 the arms 32 to swing on their pivots 34 and, as it will be remembered, the points of the block 33 are engaging the carpet, it will readily be understood that the carpet will 60 be stretched taut by the two arms 32. The rack bar 27 is lifted by the action of the two levers 28 and 29, and these levers are lifted to a perpendicular position by means of the draw rod 37 which is pivoted to each 65 lever 28 and 29, and is connected to one end

of a bell crank lever 38 which is pivoted at 39 to a bracket, and the other end of the bell crank lever 40 is connected by the link 41 to the lever 7, so that as the carpet is wound upon the winding drum the carpet 70 stretcher is simultaneously actuated.

In use, the carpet is first passed over the upper open end of the trough, and then the presser board with its smooth convex surface is lowered into position. This presser 75 board is preferably of metal but, of course, may be constructed of any suitable material and strong enough to hold the compressed air reservoir 23. A flexible hose is preferably attached to the inlet 24 of the reservoir in order to provide for the movement 80 of the presser board when being placed in operative position. The presser board with its reservoir and nozzles, may be moved backward and forward as desired in order 85 that the jets of compressed air issuing from the nozzles may strike every portion of the carpet that is being treated under the board.

The carpet is passed through the machine upside down, and as it is held taut by means 90 of the presser board and side bars or rails 3, 3', and by the carpet stretching device, the air at very high velocity issues from the nozzles and passes in between the ceiling board and the carpet. The air is prevented 95 from issuing at the rear end of the machine by the contact between the presser board and the side board 3, and is thus confined between the presser board and the carpet. The action of the air on the carpet 100 causes the carpet to shake or vibrate, and the continuous jets of air upon the carpet and through the carpet in this manner, cause the dust and extraneous matter to be blown from the carpet into the chamber 2 from 105 which it may be exhausted by suction. The above described condition exists in the machine, for the reason that as shown in Fig. 2 of the drawings, the side board 3 presses the carpet 4 against the under side of the 110 presser board 15 with sufficient force to practically and substantially close the space between the two boards against the passage of air, and the air currents are therefore compelled to pass through the carpet as the carpet passes along under the presser board. By this method of introducing the air and 115 confining it with only one outlet, the vibrating carpet is thoroughly cleaned by the direct action of the air, and the velocity of the 120 air currents most effectively carries off the dust. By means of the lever 7 the carpet is passed through the machine step by step and the entire surface or area of the carpet is thus acted upon by the jets of compressed 125 air.

Having thus fully described my invention, what I claim as new and desire to secure by Letters Patent, is:—

1. In a carpet cleaning machine, the com- 130

bination with an open casing and a presser board, means for passing a carpet between said presser board and the open casing, and means for introducing compressed air between said board and the carpet.

2. In a carpet cleaning machine, the combination with an open end chamber, means for stretching a carpet over the chamber, a presser board for holding the carpet upon the chamber, and means for introducing compressed air into the chamber through the carpet.

3. The combination in a carpet cleaning machine with an open casing having rounded side rails, of a presser board adapted to close said casing, means for supporting said board, above said casing, and means for introducing a cleaning fluid in the casing through the carpet.

4. The combination with an open casing having rounded side rails, of a presser board having a convex under surface located over said casing, and means for introducing compressed air under the board and through a

carpet held between said board and rails as 25 described.

5. In a carpet cleaning machine including an open end chamber, the combination with a presser board over the chamber having a reservoir thereon, a multiplicity of nozzles connected to the reservoir extending beyond the edge of the presser board and curved so as to deliver between said presser board and chamber, and means for removing the presser board from the chamber.

6. In a carpet cleaning machine, the combination with an open casing and a presser board, means for imparting a step by step movement to a carpet for passing it between the board and casing, and means for introducing compressed air between said board and carpet.

In testimony whereof I affix my signature in presence of two witnesses.

LINCOLN L. PORTER.
